UNITED STATES PATENT OFFICE.

ALBERT WESTLAKE, OF NEW YORK, N. Y.

PROCESS FOR MANUFACTURING AND APPLYING FIBROUS CAPS FOR BOTTLES AND OTHER CONTAINERS.

1,114,323.

Specification of Letters Patent.

Patented Oct. 20, 1914.

Application filed November 6, 1913. Serial No. 799,574.

To all whom it may concern:

Be it known that I, ALBERT WESTLAKE, a citizen of the United States, and a resident of the city, county, and State of New York, 5 have invented a certain new and useful Process for Manufacturing and Applying Fibrous Caps for Bottles and other Containers, of which the following is a specification.

The object of my invention is to provide 10 a cap of fibrous material which will have an entirely novel character when applied, and possess certain characteristics of chemical, commercial, and sanitary character, not possessed by any fibrous material now 15 known, and to apply such cap in the most effective and hygienic way to bottles, jars, and other containers, whether used for storage, transportation, or dispensing purposes.

Experience has shown that fibrous material as heretofore manufactured, when used 20 as a closure element, is either hygroscopic for lack of suitable moisture-repelling ingredients or if rendered water-proof by paraffin or other repellants, the material becomes harsh and refractory when an attempt is made to mold it to the required 25 shape to bring about an air-tight closure. Difficulties have also arisen in producing fiber which would resist the attack of chemicals either in liquid or gaseous form contained in the sealed package, and it has been 30 usual, therefore, to effect closures where fibrous material is employed as an element by using cork, metal, or some other material 35 as a part of the closure device.

To have a perfect seal for bottles and other containers it is necessary that the material of which the seal is composed should not be affected by the contents, and in most 40 cases the seal should be air-tight. Fibrous material heretofore used for this purpose has fallen short of constituting a perfect seal either from some imperfection in the material or in its application to the container.

One object of my invention is to impart 45 such characteristics to such fibrous material as will render it more sanitary, cleanly, and non-absorbent, not affected by the contents 50 of the container, nor affecting them, and which is adapted when properly applied to make a more intimate and perfect contact of the material with the bottle, jar or other container than has heretofore been the case,

thereby producing a more perfectly air-tight and effective seal or closure.

My invention is more particularly designed for use in sealing glass or porcelain bottles or containers, used for milk or drinking water, for daily distribution and consumption, which articles, being especially liable to deterioration in transit or handling, and of vital importance to the health of the community, must be surrounded with up-to-date sanitary sealing precautions. This improved fiber cap may be used for various other liquids, pickles, preserves, jellies, foods, drugs, and medicines that require cheap, effective and hygienic sealing.

I have found that ordinary wood fiber 70 paper cannot be shaped over the mouth of a bottle or container and made to hold a definite position and shape without mechanical means of retention. The paper is either tough or stiff, has uneven creases and springs 75 away upon drying after being shaped, even when shaped so as to follow the various curves of the mouth and neck of the bottle or other container. I have found this to be the case even after dipping the paper or 80 fibrous material in melted paraffin or other waxy or gummy substances, or by supplying an inner seal of waxed paper, paraffin or similar substances. I have therefore devised a process which endows fibrous material 85 with sufficient plasticity and flowing or molding and instant setting qualities to insure an absolute and accurate contact throughout its inner surface, with all interstices of the glass or other surface of the 90 bottle to which it is applied, maintaining the quality and amount of the contents against endosmosis and exosmosis and is also sufficiently strong, tenacious and durable to resist displacement or tearing during transit 95 and handling; also resisting thermal changes of extreme cold and heat, and of exposure to sun rays in temperate climates.

To carry out my invention the first thing to do, therefore is to select a suitable fiber 100 and so treat and manipulate it as to have it act during the subsequent operations and in use as it is intended to act as above stated. As paper material is most conveniently and effectively used for sealing or bottling purposes when shaped in disk form, the first step of my new process is the formation of 105 a suitable disk out of suitable fibrous ma-

terial. The thickness of this disk will vary with the demand for resistance on the part of the container contents as obviously some containers by reason of the nature of their 5 contents will require a much heavier and thicker cap than others.

In selecting the paper or other fibrous material from which the disks are to be made, it is to be noted that if fiber is employed 10 which has already been reduced to paper form, it is preferable to use uncalendered paper or paper in the soft condition of filter paper or blotting paper. If, however, a fiber is to be used before it has been brought 15 into paper form, I prefer wood fiber or grass fiber, although most any fiber of animal or vegetable origin might be used. The fibrous material, however, whether in its original condition or after conversion into paper 20 form is preferably treated with one or more of the various preparations generally employed for water-proofing paper taking care, however, that no formaldehyde or other acid ingredients remain in the fibrous material 25 after it is shaped into disks. For the same reason if calendered or water-proof paper is used as the starting point of my process, care must be taken that it should not contain any 30 objectionable ingredients. It is, however, preferable that the fibrous material should be left rough and uncalendered until a subsequent step of the process.

Having selected as many thicknesses of the desired material as may be required 35 with a view to the heaviness or lightness of the cap to be made therefrom, these thicknesses are to be coated or impregnated with some form of resinous or gummy and sticky matter of a harmless character, and 40 thus the various thicknesses required to make the desired ply are to be rolled or otherwise merged into an integral sheet or web from which the disks are afterward stamped or cut. In selecting the ingredients by which 45 the separate thicknesses are to be united into one body, attention must be had to the importance of having everything employed 50 harmless and sanitary and to insure that the fibrous material thus produced shall be water-proof, acid-proof, non-absorbent, and capable of resisting a temperature of 150° or over without softening. The second step 55 of my process consists in heating and sterilizing each disk before it is brought into juxtaposition with the bottle or other container to which it is to be applied. This step 60 consists in subjecting the disks to a temperature of about 212° F. or over for such length of time as may be required to destroy all germs which may exist therein and 65 render the disk plastic and moldable under pressure, but not long enough to cause the same to melt, flow, or fuse. The third step of my process consists in bringing this heated disk, without allowing the same to

cool appreciably, into juxtaposition with the mouth or other opening of the bottle or other container to be capped, where it may conveniently be molded into the cap shape required by the character of said container. 70 The fourth step of my process consists in bringing about a perfect and intimate air-excluding contact between what may for convenience be called the lower side of the heated disk and such portions of the container, inside and out as the cap when formed will contact with. This step consists of several 75 sub-steps, such as holding fast the initial contact between the disk and the container which is preferably at the rim of the latter, 80 forming a central depression of desired depth in the middle portion of the disk to make the desired contact with the interior of said container, bending over, around, and under the remainder of said disk and molding 85 or ironing the same into desired contact with the outside of said container. It is during this step of the process that the uncalendered or partly calendered material of 90 the disk receives its final calendering. The 95 last step of my process is cooling the now formed and applied cap to the normal atmospheric temperature, and this may be done either rapidly by the application of cooling drafts or agents, or by allowing the same to cool by radiation. Whether one or the other method of cooling is adopted, would depend upon how soon the capped container has to be handled for transportation or otherwise.

In the accompanying drawing which is diagrammatic, *a* indicates a disk of suitable fibrous material, *b*, a heating and sterilizing oven, *c*, the neck of the bottle or other container, and *d* the lower end of the stamping die or plunger head. The arrows indicate the direction of travel from the flat disk to the completed cap.

It will be found that as a result of this process when properly carried out, the fibrous material forming the cap, has shaped 110 itself to conform to all the irregularities, interstices, depressions or marks, including screw-threads, if such there be, upon the opposing material of the container. In this way I am able to obtain a closure which is 115 practically air-tight throughout its entire gripping surface and capable of resisting all ordinary displacement strains from within or without.

While the above process is, as before stated, more particularly intended for use in capping milk bottles and other containers where a quick sealing is required, and where the contents are intended to be retained only 120 under the conditions of daily transportation and use, it is applicable to the sealing of jellies and many other substances which are intended to remain sealed for longer 125 periods of time.

I claim:

The process of manufacturing and applying fibrous caps for bottles and other containers, which consists first, in preparing a disk of suitable fibrous material; second, heating and sterilizing the same; third, bringing said disk while still heated, into juxtaposition with the container; fourth, applying said heated disk to said container 10 in such manner as to form a central depression of said disk in intimate contact with the

interior of said container and to mold the rest of said disk over and around a portion of the exterior of said container and molding the same into intimate and air-tight contact therewith; and lastly, cooling the cap thus formed to normal atmospheric temperature.

ALBERT WESTLAKE.
